SPECIFICATION forming part of Design No. 20,554, dated March 3, 1891.

Application filed February 6, 1891. Serial No. 380,513. Term of patent 3½ years.

To all whom it may concern:

Be it known that I, HENRY O. SCHMIDT, a citizen of the United States, residing in New York, in the county and State of New York, 5 have invented and produced a new and original Design for Cane or Umbrella Handles, of which the following is a specification, reference being had to the accompanying drawing, forming part thereof.

10 In the drawing is shown a side elevation of a cane or umbrella handle illustrating my new design.

The shank A is made somewhat fan-shaped, having an enlarged flattened head B at the 15 top. The middle portion of the sides of the shank A are ornamented by flower-work, as at D. The upper portion of the shank is ornamented by a series of ribs F, running in opposite directions, as shown. The upper

portion of the shank is flattened, while the 20 lower portion is rounded or cylindrical and is mounted by an annular band C, ornamented. The entire handle may be further ornamented by a corded edge, substantially as shown.

The handle may be made of any suitable 25 material.

Having now described my design, what I claim as new, and desire to secure by Letters Patent, is—

The design for cane or umbrella handles, 30 substantially as herein described and shown.

In testimony of which invention I have hereunto set my hand.
